ANIMATED TOY FIGURE

Arthur M. Hillery, Leominster, Mass.

Application May 5, 1950, Serial No. 9,722

Term of patent 7 years

(Cl. D34—4)

To all whom it may concern:

Be it known that Arthur M. Hillery, a citizen of the United States, residing at Leominster, in the county of Worcester and State of Massachusetts, has invented a new, original, and ornamental Design for Animated Toy Figure, of which the following is a specification, reference being had to the accompanying drawing, forming part thereof.

Fig. 1 is a view in front elevation of an animated toy figure, showing my new design; and

Fig. 2 is a view in side elevation thereof on a reduced scale.

I claim:

The ornamental design for an animated toy figure, as shown.

ARTHUR M. HILLERY.
